(57) **CLAIM**

The ornamental design for a divided plate as shown and described.

DESCRIPTION

FIG. 1 is a left perspective view of a divided plate; FIG. 2 is a right perspective view thereof;

FIG. 3 is a front view thereof;

FIG. 4 is a rear view thereof;

FIG. 5 is a right view thereof;

FIG. 6 is a left view thereof;

FIG. 7 is a top view thereof; and

FIG. 8 is a bottom view thereof; and,

FIG. 9 is an enlargement view of FIG. 3.

The broken lines in the drawings depict portions of the divided plate that form no part of the claimed design. The dot dot dash broken lines in the drawings depict the boundaries of the magnified view of FIG. 9 and form no part of the claimed design.

1 Claim, 8 Drawing Sheets
